CLAIM

The ornamental design for a journal bearing for a carrier for paper rolls, as shown and described.

DESCRIPTION

FIG. 1 is a side elevation of a journal bearing for a carrier for paper rolls showing my new design together with an exemplary bearing pin for a paper roll;

FIG. 2 is a side elevation thereof, rotated about 90 degrees relative to FIG. 1;

FIG. 3 is a side elevation of a journal bearing for a carrier for paper rolls showing my new design together with an exemplary end cap for a core of a paper roll;

FIG. 4 is a side elevation thereof, rotated about 90 degrees relative to FIG. 3;

FIG. 5 is a perspective view of the journal bearing showing my new design;

FIG. 6 is a top plan view thereof;

FIG. 7 is a side elevation thereof;

FIG. 8 is a bottom plan view thereof; and,

FIG. 9; is a side elevation showing the bearing pin rotated about 90 degrees relative to FIG. 7.

The broken lines shown in the drawings illustrate environmental structure and form no part of the claimed design.
